UNITED STATES PATENT OFFICE.

GUS ELLIS TALLEY, OF PHOENIX, ARIZONA, ASSIGNOR OF ONE-HALF TO WILLIAM ALANZO BENNETT, OF PHOENIX, ARIZONA.

COTTON GIN.

Application filed December 7, 1926. Serial No. 153,163.

The present invention relates to gins of the roller type, and the object is to provide a novel apparatus in which the ginning action is effective and thorough both for long 5 and short staple, and is furthermore rapid in its action, thus materially increasing the output.

A further object is to provide mechanism whereby nails, stones or other obstructions 10 will not cause injury or create dangerous conditions, but will pass readily through the machine.

The preferred embodiment of the invention is illustrated in the accompanying 15 drawings, wherein:—

Figure 1 is a front elevation of the gin, 20 Figure 2 is a plan view with the top of the crank housing removed,

Figure 3 is an end elevation,

Figure 4 is a sectional view on the line 4—4 of Figure 3,

Figure 5 is a sectional view on the line 5—5 of Figure 1 and on an enlarged scale,

Figure 6 is a front elevation of the supporting bar and the knife member mounted thereon, the stripper blade being also shown,

Figure 7 is a top plan view of the carrier bar and stripper blade mounted therein,

Figure 8 is a front elevation of the carrier 30 bar,

Figure 9 is a sectional view on the line 9—9 of Figure 3.

In the embodiment disclosed, a frame is employed, comprising end members 10 connected by a suitable base 11, and having a Y brace 12 secured to the central portion of the base 11 and bolted to the end members 10 between their upper and lower portions.

The rear upper corners of the end members are cut-away, as illustrated at 13, forming seats, upon which bearing boxes 14 are slidably mounted, that are adapted to be held by suitable bolts 15. Adjusting screws 16 serve to move the boxes inwardly. Journaled in these boxes is a shaft 17 having a squared portion 18, on which is mounted the body 19 of the gin roller. This body is covered with suitable material, such as strips of walrus hide, shown at 20, diagonally wound on and secured to the roller body in a manner well understood. The roller is rotated by any suitable means in the direction indicated by the arrows in Figures 3 and 5.

Located below the roller is a supporting

bar 21 held by bolts 22 that pass through slots 23 in the ends of the bar 21, these slots thus permitting the vertical adjustment of the supporting bar. Its upward movement is secured by means of adjusting screws 24 60 that bear against its lower side. In the upper edge of the bar is formed a longitudinal groove 25, constituting a seat, and in this seat is located the lower edge of an upstanding knife member 26, having a sharpened 65 upper edge 27 that lies alongside the downwardly moving surface of the gin roller. The blade is secured in place by U-shaped clamp plates 28 bearing against the front face of the bar and the lower margin of 70 the blade 26. These clamp plates are held in place by bolts 29. Spring plates 30, having offset ends, also bear against the front face of the supporting bar 21 and the front face of the blade 26, their tension being obtained by bolts 31 (see Figure 6). As a consequence it will be evident that the upper portion of the knife member will be held yieldingly against the face of the roller and that said knife member can be vertically 75 adjusted by adjusting the supporting bar 21. It will also be evident that the roller can be adjusted toward and from the blade, as desired.

Located in advance of the roller and 80 knife member 26 is a carrier bar 32, the ends of which extend through the end members 10 of the frame and have terminal eyes 33 in which are fixed studs 34 held by set screws 35 and projecting on opposite sides 90 of the eyes 33. Flexible upstanding arms 36 are provided at their upper ends with journal boxes 37, in which the studs 34 are pivotally engaged. The lower ends of the arms 36 are bolted, as shown at 38 to vertically 95 adjustable plates 39, and these plates are in turn mounted on horizontally adjustable plates 40 that are carried by the outer sides of the end members 10. As shown in Figures 3 and 9, the horizontal 100 plates are held by bolts 41 passing through both plates, and through the end members 10, and are horizontally adjustable by means of adjusting screws 42, horizontal slots of course being provided in the plates 40 for 105 the passage of the clamping bolts 41. The vertically adjustable plates 39 are secured by the bolts 41 and have vertical slots 43, through which said bolts 41 pass. The vertical adjustment of the vertically movable 110

plates is secured by adjusting screws 44 threaded through ears 45 formed on the upper ends of the plates 39, and bearing on the upper edges of the plates 40. It will thus be evident that the carrier bar is capable of longitudinal movement.

This movement is effected through the medium of a crank shaft 46 journaled in a casing 47 that is carried by one of the end members 10. The crank of this shaft 46 has a journal box 48 engaging it, and this box is connected to a flexible pitman 49. The pitman is secured by bolts 50 to the central portion of the carrier bar 32, as clearly shown in Figures 1, 2 and 8. Upon the rotation of the crank shaft 46, it will be evident that the carrier bar will be rapidly reciprocated.

A stripper blade 51, coacting with the front face of the knife member, is mounted on the carrier bar 32. This blade preferably has its upper edge serrated, as shown at 52, and it is so disposed that the upper edge of the knife member extends across the rear faces of the teeth and the interdental spaces of the stripper blade. The stripper blade is mounted on the carrier bar by a series of bolts 53 that slidably pass through openings in the carrier bar and are held in place by nuts 54 that are on the bolts and bear against opposite sides of the bar. With this construction, it will be clear that the bar can be raised, lowered or shifted horizontally by moving the plates on which the flexible arms 36 are mounted, and in addition the stripper blade can be adjusted toward and from the carrier bar and therefore toward and from the knife member by adjusting the bolts 53 in the carrier bar 32.

Mounted on this carrier bar and extending thereover is a rearwardly and downwardly inclined feed table 55 that may be formed of corrugated sheet metal. As shown in Figure 5, this table terminates short of the stripper blade 51 and is adjustably held in place by screws 56 passing through slots 57 in the table.

The operation of the structure is substantially as follows. With the roller rotating in the direction indicated by the arrow and with the crank shaft 46 rotating, it will be evident that the downwardly moving surface of the roller passes by and in close association with the upstanding edge of the knife member, and that the serrated edge of the stripper bar operates directly in front of the same. If now seed cotton is deposited on the table 55, it will be caused to gravitate rearwardly by reason of the reciprocation of the table and the inclination thereof. Consequently the lint will be brought into contact with the downwardly moving face of the roller, and adhering thereto, will be drawn behind the stripper bar and knife member. It will therefore find its way

downwardly and rearwardly behind the knife member, and over the inclined rear upper face of the supporting bar. The seed, however, will be held back, and being dislodged by the reciprocating stripper blade, will pass downwardly behind the table 55 due to the space between the rear edge of the table and the stripper blade 51, thence said seed can gravitate between the carrier bar 32 and the front face of the blade, the space being left for that purpose. It is thought that this can be readily understood by reference to Figure 5. Any stones, nails or other hard obstructions will be held away from the roller and knife member by the stripper so that these too will pass downwardly with the seed and consequently will not be brought into frictional engagement with the portion of the roller that is engaged with the knife member. They therefore will neither obstruct the machine and its operation, nor cause dangerous conditions from their presence in the seed cotton. It has been found that with this apparatus, the cotton can be ginned with great rapidity and very effectively. Obviously any adjustment that is necessary can be obtained either by vertically adjusting the supporting bar 21, the knife member 26, the gin roll or the stripper blade as may be found desirable.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

What I claim, is:—

1. In a cotton gin of the character set forth, the combination with a rotatable gin roller and means for rotating it in a predetermined direction, of a stationary upstanding knife member having its upper edge located along the downwardly moving face of the roller, an upstanding longitudinally movable stripper blade located alongside the knife member, means for reciprocating the stripper blade, a feed table for delivering seed cotton to the downwardly moving face of the roller over the upper edges of the knife and stripper blade, said table being movable with the stripper blade, said downwardly moving face of the roller acting to draw the fiber downwardly over the upper edges of the knife member and stripper blade, and means for mounting the table and knife in spaced relation to permit the seed to pass between them.

2. In a cotton gin of the character set forth, the combination with a rotatable gin roller and means for rotating it in a predetermined direction, of an upstanding

- knife member having its upper edge located alongside the downwardly moving face of the roller, a longitudinally movable carrier bar mounted in advance of the knife member, means for longitudinally reciprocating the bar, an upstanding stripper blade having a serrated upper margin alongside the knife margin, said stripper blade being spaced from the carrier bar, said downwardly moving face of the roller acting to draw the fiber downwardly over the upper edges of the knife member and stripper blade, means for mounting the blade on the bar, and a feed table mounted on and reciprocating with the bar and terminating short of the stripper blade, the space between the stripper blade and the bar and table constituting a discharge outlet for the seed. 65
3. In a cotton gin of the character set forth, the combination with a frame, of a rotatable gin roller, a knife member located along one side of the roller, flexible arms fixed at their lower ends to the frame, a longitudinally movable carrier bar mounted on the upper ends of the flexible arms, a stripper blade mounted on the carrier bar and operating alongside the knife member, and means for flexing the arms to reciprocate the carrier bar and stripper blade. 70
4. In a cotton gin of the character set forth, the combination with a frame, of a rotatable gin roller, a knife member located along one side of the roller, flexible arms, means for adjustably mounting the lower ends of the arms on the frame, a longitudinally movable carrier bar mounted on the upper ends of the flexible arms, a stripper blade mounted on the carrier bar and operating alongside the knife member, and means for flexing the arms to reciprocate the carrier bar and stripper blade. 75
5. In a cotton gin of the character set forth, the combination with a frame, of a rotatable gin roller, a knife member located along one side of the roller, mounting plates adjustably mounted in opposite sides of the frame, other plates mounted on the first plates and adjustable thereon at right angles to the paths of adjustment, flexible upstanding arms fixed to the second plates, a longitudinally movable carrier bar mounted on the upper ends of the flexible arms, a stripper blade mounted on the carrier bar and operating alongside the knife member, and means for flexing the arms to reciprocate the carrier bar and stripper blade. 80
6. In a cotton gin of the character set forth, the combination with a frame, of a rotatable gin roller, a knife member located along one side of the roller, mounting plates horizontally slidable on opposite sides of the frame, means for adjusting the plates and securing them in adjusted position, other plates vertically slidable on the horizontally adjustable plates, means for vertically adjusting the plates and holding them in adjusted position, flexible upstanding arms fixed to the second plates, a longitudinally movable carrier bar mounted on the upper ends of the flexible arms, a stripper blade mounted on the carrier bar and operating alongside the knife member, and means for flexing the arms to reciprocate the carrier bar and stripper blade. 85
7. In a cotton gin of the character set forth, the combination with a frame, of a rotatable gin roller and means for rotating it in a predetermined direction, a stationary supporting bar below the same, an upstanding knife member fixed to the bar and coacting with the downwardly moving face of the roller, a reciprocatory carrier bar in advance of the supporting bar and roller, flexible arms supporting the same, a driving crank, a flexible pitman driven by the crank and fixed to the carrier bar, and an upstanding stripper blade mounted on the carrier bar and having its upper edge coacting with the knife member. 90
8. In a cotton gin of the character set forth, the combination with a frame, of a rotatable gin roller and means for rotating it in a predetermined direction, a stationary supporting bar below the same, an upstanding knife member fixed to the bar and coacting with the downwardly moving face of the roller, means for adjusting the roller toward the knife member, means for vertically adjusting the supporting bar, a reciprocatory carrier bar in advance of the supporting bar and roller, flexible arms supporting the same, a driving crank, a flexible pitman driven by the crank and fixed to the carrier bar, mountings for the flexible arms that are vertically and horizontally adjustable, an upstanding stripper blade coacting with the knife blade, and means for mounting the stripper blade on the carrier arm and permitting its adjustment towards and from the knife member. 95
9. In a cotton gin of the character set forth, the combination with a gin roller and means for rotating it in a predetermined direction, of an upstanding knife member having its upper edge located along the downwardly moving face of the roller, a bar located in advance of the blade, means for longitudinally reciprocating the bar, a stripper blade carried by the bar and operating alongside the knife member, and a feed table mounted on the bar and reciprocating with the bar and stripper blade. 100
